FIG. 1

Inventor
Rudolph Coopersmith

By
International Co
A.H.S.

UNITED STATES PATENT OFFICE.

RUDOLPH COOPERSMITH, OF MONTREAL, QUEBEC, CANADA, ASSIGNOR OF ONE-HALF
TO ABRAHAM RUCHE, OF PHILADELPHIA, PENNSYLVANIA.

SPRING-MATTRESS.

1,369,325.

Specification of Letters Patent. Patented Feb. 22, 1921.

Application filed March 1, 1920. Serial No. 362,204.

To all whom it may concern:

Be it known that I, RUDOLPH COOPERSMITH, a citizen of the United States, and resident of the city of Montreal, in the 5 Province of Quebec and Dominion of Canada, have invented certain new and useful Improvements in Spring-Mattresses, of which the following is a full, clear, and exact description.

10 This invention relates to improvements in spring mattresses, and the object of the invention is to provide a mattress so constructed that the entire width thereof contributes to the support of a person lying 15 on any part of the mattress.

A further object is to provide a spring which may be easily and cheaply manufactured.

Another object is to provide a spring free 20 from projections which wear out an upholstered mattress placed thereon.

The device consists briefly of a rectangular frame of any suitable form having head and foot rails between which a fabric 25 according to this invention is stretched. The fabric comprises angularly disposed strands interwoven and extending between the head and foot rails, to which they are attached by means of helical springs. The 30 ends of certain of these angularly disposed strands are attached to heavier strands or marginal members extending between and at right angles to the head and foot rails and supported therefrom by springs.

35 In the drawings which illustrate the invention;—

Figure 1 is a partial plan view of a spring mattress or bed bottom according to this invention.

40 Fig. 2 is a side elevation of the device.

Referring more particularly to the drawings, 11 designates the head and foot rails of a frame which are held apart by side rails 12. The bed bottom fabric comprises 45 a plurality of angularly disposed strands 13, which extend between the head and foot rails or between one of these rails and a marginal member 14, which is supported between the head and foot rails and at right angles thereto by springs 15. The strands 13 may be wires or thin flat bands of metal or may be of any other suitable material and are preferably but not necessarily interwoven, as shown in Fig. 1. The ends of 55 each strand are connected to the frame or to

the frame and marginal members 14 by helical springs 16. Preferably, the angular arrangement of the strands is such that the supporting springs of two converging strands may be attached to a single hole 17 60 formed in the rails 11, so that the manufacturing cost of the device is kept as low as possible. The degree of angularity of the strands with respect to the frame members may be altered as desired, but it has 65 been found that for all practical purposes, the best results are obtained when the strands extend parallel with lines extending from approximately the center of one end rail to the corners of the other rail (in 70 a double bed mattress). At the corners of the mattress where very little weight is to be supported, the strands may extend in one direction only, that is, the short crossing strands may be omitted, as shown in Fig. 1. 75 It will be understood, however, that the corners may be filled in in the same manner as the center of the structure. In order to facilitate the attachment of the strands and their springs to the marginal members 14, 80 the inner edges of these members may be provided with notches 18 having their sides 19 parallel with the strands and their ends 20 transverse of the strands. These notches receive the springs as shown and avoid all 85 possibility of the springs rubbing on the edge of the member 14, as would be the case if it were not notched.

It will be obvious from Fig. 1 that the weight of a person lying on any part of this 90 fabric will be supported by substantially all the helical springs 16, owing to the angular arrangement of the strands 13. In fact, a load placed on any portion of one strand is sustained to a certain extent by every intersecting strand and as these intersecting strands intersect strands parallel with the first, the load is distributed over substantially the whole structure. The angular disposition of the strands avoids the local 100 sagging of the structure, such as is commonly found in fabrics having longitudinal extending members. This elimination of sagging is due to the fact that all the supporting springs receive substantially equal 105 load.

While the strands are preferably interwoven to avoid rattling, the invention is not limited to such interweaving. It will be obvious that while the strands have been 110

shown connected directly by the springs to the end rails, transverse bars may be interposed between the strand ends and springs. It will also be obvious that the marginal members 14 may be attached directly to the end rails without the interposition of the springs 15, thus producing a rigid, rectangular frame. By altering the angle at which the strands lie to the end rails, oppositely inclined strands may be connected to the same point of the marginal members in the same manner in which they are connected to the same point of the end rails.

Having thus described my invention, what I claim is:—

1. In a bed bottom fabric, end rails, continuous strands extending between said rails at predetermined angles thereto, flexible marginal members resiliently supported be-

tween the extremities of the end rails, said marginal members being notched at adjacent edges, and further strands parallel with the first named extending between an end rail and a marginal member, and springs connecting said further strands to the rails and marginal members, the springs connecting to the marginal members being received in the notches thereof.

2. In a bed bottom fabric, end rails, marginal members resiliently connected at the ends to said end rails, and strands extending in straight lines between the two end rails and between the marginal members and the end rails.

In witness whereof, I have hereunto set my hand.

RUDOLPH COOPERSMITH.
